UNITED STATES PATENT OFFICE.

BUREN M. SOULE, OF CEDAR RAPIDS, IOWA.

CARRIAGE-SPRING.

SPECIFICATION forming part of Letters Patent No. 400,134, dated March 26, 1889.

Application filed July 30, 1888. Serial No. 281,374. (No model.)

To all whom it may concern:

Be it known that I, BUREN M. SOULE, a citizen of the United States of America, residing at Cedar Rapids, in the county of Linn and State of Iowa, have invented certain new and useful Improvements in Carriages and Wagons, of which the following is a specification.

My invention has relation to springs and body-supports for road-vehicles; and the object is to provide improved body-supports and springs to the running-gear of road-vehicles, whereby the body will be supported with or without the springs and at the same time in association with the springs, there will be imparted to the body an improved resiliency.

With this object in view my invention consists in the novel construction of parts and their combination, as hereinafter specified, and specially as the same is particularly pointed out and distinctly claimed, as required by statute.

I have fully illustrated my improvements in the accompanying drawings, wherein Figure 1 is a bottom plan view of the side supports and springs. Fig. 2 is a view of one of the springs detached. Fig. 3 is a view of the naked supports. Fig. 4 is a view of the supports and springs with a body mounted thereon, and Fig. 5 shows the supports having but one spring.

Reference being had to the drawings, A designates the side bars of the running-gear connected at the ends by the cross-bars or springs B.

C designates the body-frame of the vehicle, having secured across it the cross-pieces 1, 2, 3, and 4. On these cross-pieces are secured bearings 5, in which are disposed my improved supporting-rods D. These supporting rods or bars are of such substantialness as to serve the purposes to which they are put without breaking or bending out of shape. They consist of two metal bars bent at the middle into loop forms 6 7, and having both ends bent outward, as at 8, and provided with shackles or clips 9, to attach them to the side bars of the running-gear. The loop forms are projected inward under the body of the vehicle and are linked together, one within the other, as shown at 10, and in this connection are given a proper play to permit the springs to

have the proper resiliency. The bars are mounted in the bearings 5 and secured thereon by suitable bearing-caps. It will be observed from the arrangement of these supporting-bars that although the vehicle should become entirely deprived of its springs the body would ride level and with convenience and safety to the occupants.

E designates the springs. These consist of substantial steel rods formed with spirals 11, connected by a loop or bail, 12, and projecting ends 13. These spirals are mounted on a rod, 14, having its ends in bearings in the cross-pieces of the body-frame to give them stability, and the loop of the spring is arranged with the end to bear upon the loop of the supporting-rods, and the ends of the springs are anchored on the cross-pieces, as at 15. This gives the springs a torsional function, so that when a weight is imposed on the body of the vehicle the tendency of the supports to lower the body by turning in their bearings is restrained by the force of the springs on the loops of the supports and a decided and positive resiliency imparted to the body.

As shown in Fig. 5 of the drawings, one spring may serve the purpose; but to preserve the uniformity of tension, increase the durability, and make a more slight association of elements two springs are generally used.

It will be perceived that the body is supported equally at all points, so as to maintain a true horizontality, and that all the movements are in substantially a vertical plane. The supporting-rods are operative independently of the springs—that is, they will serve the purpose of supports without the application of the springs.

While I have shown and described the supports and springs arranged on the sides of the body, it is apparent that they may be applied with equal adaptability to the ends of the body.

What I claim is—

1. The combination, with the side bars and body of a road-vehicle, of the supporting-rods D, arranged parallel with each other and formed with loop forms or bails, which are linked together one within the other and hav-

ing the ends shackled to the bars of the running-gear, substantially as shown and described.

2. The combination, with the supporting rails or bars and body of a road-vehicle, of supporting-rods mounted in bearings on the body and formed at their middle with bails or loops linked together one within the other, and the ends of the bars shackled to the bars of the body-frame, and a spring, E, mounted on the bottom of the body-frame and formed to bear with its force on the interlinked loops of supporting-rods, substantially as and for the purpose specified.

15 3. The combination, with the supporting rails or bars and the body of a road-vehicle, of supporting-bars mounted in bearings on the bottom of the body and formed with loops linked together one within the other, and having the ends of the bars shackled to supports, and springs E, mounted on the bottom of the body-frame and adapted to bear with their force on the interlinked loops of the supporting-bars, substantially as described.

20 4. The combination, with the supporting rails or bars and the body of a road-vehicle,

of supporting-bars A, mounted in bearings on the bottom of the body and formed with loops at their middle, said loops being linked together one within the other, and having the ends of the bars shackled to supports on the running-gear of the vehicle, and springs E, mounted on the bottom of the body, said springs consisting of spirals connected by a loop, arranged to bear on the interlinked loops of the supporting-bars, substantially as shown and described.

25 5. In a road-vehicle, the combination of parallel body-supporting bars, formed at their middle portions with loops linked one within the other and their free ends adapted to be connected to supports, and springs formed with loops to set over the loops of the supporting-bars to impart a resilient movement to the bars, substantially as described.

In witness whereof I have hereunto set my hand in the presence of two attesting witnesses.

BUREN M. SOULE.

Attest:

I. N. WHITTAM,
H. S. JOSSELYN.
